United States Patent Office.

B. R. BOYNTON, OF KEESEVILLE, NEW YORK.

Letters Patent No. 68,551, dated September 3, 1867.

IMPROVED BED-BOTTOM.

The Schedule referred to in these Letters Patent and making part of the same.

TO ALL WHOM IT MAY CONCERN :

Be it known that I, B. R. Boynton, of Keeseville, in the county of Essex, and in the State of New York, have invented certain new and useful improvements in Bed-Bottom; and do hereby declare that the following is a full, clear, and exact description thereof, reference being had to the accompanying drawing, and to the letters of reference marked thereon.

Figure 1 is a plan view of my invention.

Figure 2 is an end view of the same.

The object of my invention is to provide a bed-bottom which shall be cheap and simple in its construction, and which is adapted to beds of all kinds, and consists in the arrangement and combination of certain devices, which shall be fully explained and set forth hereafter.

A represents the cross-pieces upon which the bottom rests. Attached to cross-pieces A are the coiled springs B, to which the slats C are secured. The upper ends of the springs B are shaped like a loop, and thrust through the openings or slots cut near the ends of the slats C, (as seen in fig. 1.) A leather strap, D, is then passed through the ends of the springs, so as to hold the slats in their places, and is then buckled or secured to both ends of the cross-pieces A. By means of straps D the amount of springiness or elasticity of the springs can be controlled at pleasure, by tightening or loosening the ends of the straps, as the case may require.

What I claim as new, and desire to secure by Letters Patent, is—

Providing the slats with slots, and the springs with loops upon their upper ends, said loops being passed through the slots and confined by means of straps, substantially as specified.

In testimony that I claim the foregoing I have hereunto set my hand this 23d day of July, 1867.

B. R. BOYNTON.
